UNITED STATES PATENT OFFICE.

WILLIAM E. QUIMBY, OF NEW YORK, N. Y.

BRAKE FOR ADMINISTERING PRESCRIBED RESISTANCE TO THE STARTING MOVEMENTS OF HAND-OPERATED CONTROLLERS.

SPECIFICATION forming part of Letters Patent No. 703,468, dated July 1, 1902.

Application filed December 7, 1900. Renewed December 13, 1901. Serial No. 85,844. (No model.)

To all whom it may concern:

Be it known that I, WILLIAM E. QUIMBY, of the city and State of New York, have invented a certain Improvement in Brakes for

5 Administering Prescribed Resistance to the Starting Movements of Hand-Operated Controllers, of which the following is a specification.

The object of this invention is to guard 10 against the too rapid starting of trolley-cars. It is accomplished by imposing such resistance to the manually-effected starting movements of the controller as will compel such movements to be made slowly.

15 The invention consists in the combination of the controller-operating shaft with a vacuum-cylinder and piston and connections between said shaft and said piston whereby the starting movement of the controller is opposed by atmospheric pressure acting on said piston.

The accompanying drawings of a simple form of mechanism embodying an illustration of the invention are as follows:

25 Figure 1 is a vertical section of so much of the upper part of an ordinary controller-box as is necessary to show the vacuum-cylinder, the piston, and the connections thereof with the controller-operating shaft. Fig. 2 is a 30 horizontal section taken through the plane indicated by the dotted line $x-x$ on Fig. 1.

The drawings show a portion of the shell a of an ordinary controller-box, such as used on the platform of trolley-cars. The head b 35 of the box is perforated to admit of the extension through it of the controller-operating shaft c , to the upper extremity of which is attached the usual operating-crank d , adapted to be engaged at either end of its rotating excursions by the usual stop e , erected upon the head b of the box. The shaft c has affixed to it the toothed pinion f , adapted to engage the teeth of the endwise-sliding rack-bar g , affixed to or formed integrally with the piston h , which traverses the vacuum-cylinder i .

The parts are so organized that at the commencement of the starting movement of the crank d the piston f is in close proximity to

the hinged head j of the cylinder, which when the piston f recedes from it is held by atmospheric pressure against the end i' of the cylinder i .

50 The periphery of the piston h may be provided with any suitable packing—as, for example, if desired, with the cup-packing h' . 55 The cylinder may be provided with the leak-inlet k , susceptible of being wholly or partially closed by the adjustable screw-plug k' for varying the resistance to the outward stroke of the piston as may be desired.

60 The hinged head j of the cylinder i constitutes a check-valve which is normally held on its seat by gravity and is kept closed by atmospheric pressure during the stroke of the piston induced by the starting movement 65 of the controller-shaft, but which by yielding freely during the return stroke of the piston opens an outlet of ample area for the escape from the cylinder of the air at that time in front of the advancing piston.

70 What is claimed as the invention is—

1. In electric starting mechanism the combination of the controller-operating shaft with a vacuum-cylinder; a piston traversing said cylinder and connections between said operating-shaft and said piston, whereby the starting movements of the controller are opposed by atmospheric pressure acting upon said piston.

75 2. In electric starting mechanism, a vacuum-cylinder provided with an outwardly-yielding check-valve; a piston adapted to traverse said cylinder, in combination with the controller-operating shaft and connections between said piston and said controller-operating shaft, whereby the starting movement of the controller-operating shaft is opposed by atmospheric pressure acting upon said piston and its opposite movement is unopposed by such pressure.

80 3. In electric starting mechanism, a vacuum-cylinder provided with an adjustable leak-inlet; a piston traversing said cylinder; in combination with the controller-operating shaft and connections between said controller-operating shaft and said piston, whereby the starting movement of the controller-operating

shaft is opposed by a prearranged amount of unbalanced atmospheric pressure acting upon said piston.

4. In electric starting mechanism, a vacuum-cylinder provided with an outwardly-yielding check-valve and with an adjustable leak-inlet; a piston traversing said cylinder; in combination with the controller-operating

shaft and connections between said controller-operating shaft and said piston, as and for the purpose set forth.

WILLIAM E. QUIMBY.
